(57) **CLAIM**

The ornamental design for a flooring clip as shown and described.

DESCRIPTION

FIG. 1 is a front, left, top perspective view of a flooring clip showing the new design;

FIG. 2 is a rear, right, bottom perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom view thereof.

The broken lines in the drawings illustrate portions of the flooring clip that form no part of the claimed design.
